Primary Examiner — Messina L Smith*Assistant Examiner* — Angela C. Ligon(74) *Attorney, Agent, or Firm* — Ying-Ting Chen; Law Office of Michael Chen(57) **CLAIM**

The ornamental design for a wireless charging holder, as shown and described.

DESCRIPTION

FIG. 1 is a perspective view of a wireless charging holder showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines depict portions of the wireless charging holder that form no part of the claimed design.

1 Claim, 8 Drawing Sheets(56)
